THERMOSTATIC SWITCH

Filed July 18, 1930

INVENTOR
Earl K. Clark

BY
Wesley S. Barr
ATTORNEY

UNITED STATES PATENT OFFICE

EARL K. CLARK, OF MANSFIELD, OHIO, ASSIGNOR TO WESTINGHOUSE ELECTRIC & MANUFACTURING COMPANY, A CORPORATION OF PENNSYLVANIA

THERMOSTATIC SWITCH

Application filed July 18, 1930. Serial No. 468,854.

My invention relates to thermal devices and particularly to thermostatic switches.

An object of my invention is to provide a relatively simple and compact thermal device which shall cause a plurality of movements of one contact member relatively to a cooperating contact member.

Another object of my invention is to provide a relatively simple and inexpensive structure for the thermostatic control of heating elements which are to be operated at a plurality of different temperatures.

In practicing my invention, I provide a base member, of substantially bar shape, a movable contact bar structure, of substantially U-shape, and a pair of substantially co-extensive and spaced bimetal bars to actuate the contact structure of U-shape in a plurality of predetermined directions relatively to a fixed contact member or members.

In the single sheet of drawings,

Figure 1 is a view, partially in side elevation and partially in section, of a thermostatic switch assembly embodying my invention;

Fig. 2 is a view in end elevation thereof;

Fig. 3 is a top plan view of the device with the casing removed;

Fig. 4 is a view in side elevation with the cover shown in section of a modified form of device embodying my invention, and

Fig. 5 is a view in end elevation thereof.

Referring more particularly to Figs. 1 to 3, inclusive, I have there illustrated a metal base plate 11 which is provided with an intermediate inwardly bent portion 12. The right-hand end portion of the base member 11 is provided with a recess 13 for receiving therein a terminal-supporting member 14 of electric-insulating material. A plurality of adjustable contact members 16, 17 and 18 extend through the member 14 and may be locked in any adjusted position by nuts 19 thereon.

A contact spring member 21, of substan-

tially U-shape, has one end portion thereof secured to the base, as by rivets 22 at the portion 12 of the base. A contact member 23 is secured to the other end of the member 21 closely adjacent to the end of the arm and in such position as to operatively engage contact terminal 16. A relatively thin metal plate 24 has one of its ends riveted to an intermediate portion of the upper part of the member 21 as by rivets 26. The other end of member 24 is slit so as to provide two arms 27 and 28, each of which arms are provided with contact members 29 and 31, respectively, so located as to operatively engage terminals 17 and 18.

A bimetallic strip 32 has one end thereof secured against the end portion of spring contact member 21 by the rivets 22 and extends toward the intermediate portion of member 21, the free end thereof being provided with a bent-out portion 33 which operatively engages the spring contact member 21. A second bimetal strip 34 has one end thereof secured to a resilient support 36 in the shape of a bar which has one end thereof secured by the rivets 22 to the intermediate portion 12. The other end of member 36 is suitably secured as by welding or by a rivet 37 to the substantially fixed end of bimetal bar 34. The other end of the bar 34 is adapted to engage the upper portion of spring contact arm 21, but initially there is a small clearance between the free end of the arm 34 and more particularly between the bent-out portion 33 and the inner face of arm 21, for a purpose to be hereinafter specified.

In order to permit of adjusting the switch assembly and thereby to vary the temperature at which the device will operate, a machine screw 41 extends through one part of the base plate 11 adjacent to one end and through the members 21 and 32 and engages rivet 37 and may be locked in any position by a lock nut 42.

A casing 43, of substantially U-shape, fits over the edge portions of base plate 11.

90

Referring to Figs. 4 and 5 of the drawing, I have there shown a substantially similar base plate 51, and a contact terminal-supporting member 52, of electric-insulating material, with a plurality of terminals 53, 54 and 56 extending therethrough and held by lock nuts 57. The spring contact member of substantially U-shape is here made in two portions including a portion 58 of substantially 16 U-shape and a bar 59 which has associated therewith a double arm contact element 61 as was hereinbefore set forth for the arm 24 shown in Fig. 1 of the drawing.

A bimetal strip 62 has one end secured to 15 the base 51 as by rivets 63 and has its other end operatively engaging one leg portion of the member 58. A second bimetal bar 64 has one end thereof secured to a spring supporting member 66, the other end of which 20 is secured to the base 51 by the rivets 63. The free end of bimetal bar 62 is bent laterally first in one direction and then in the reverse direction from the plane of the rest of the bar to constitute a pocket of V-shape to receive the end of portion 67 of the arm 59 in abutting relation, the arm 59 and the member 58 constituting, in effect, a spring contact member of substantially U-shape.

A small machine screw 68 extends through 30 the base 51 and through openings in member 58 and bimetal bar 62 into operative engagement with the end of spring arm 66, in order to adjust the device, a nut 69 being provided on the screw 68 to lock it in any desired adjusted position. A casing 71 of U-shape, is adapted to slidingly fit over the edge portions of base member 51.

The device embodying my invention was designed particularly for use with warming 40 pads and one or more of these thermostatic switches may be located in the warming pad so as to control the temperature thereof.

The heating element of a warming pad or, in fact, of any electrically heated device, is 45 represented by heating element 73 and a manually operable switch 74 is provided having a movable contact arm which may be moved selectively into engagement with fixed contact members 76, 77 or 78. The contact members 50 76, 77 and 78 are connected, by suitable conductors, to the terminals 16, 17 and 18 or in the device shown in Fig. 4 to terminals 53, 54 and 56.

Assuming that the device has been properly 55 adjusted and that contact arm of switch 74 is in engagement with contact member 76, I have found it possible to maintain an average temperature in a warming pad on the order of 120° F. If contact member 77 is engaged, 60 I have found that an average temperature of 150° F. may be maintained, while, if contact member 78 is engaged by the switch arm, an average temperature of 180° F. may be maintained.

65 The movable contact structure, including

the arms 21 and 24 or 59 and 61, provides a spring contact structure including a plurality of arms of different degrees of rigidity, and I have found that a quick clean break or disengagement of cooperating contact members is effected by my device. More important, however, is the operation of the two bimetal strips, and I will explain such action by reference to Figs. 1 to 3, it being understood that the operation of the device illustrated in Figs. 4 and 5 is substantially the same.

As was hereinbefore stated, the movable end of bimetal bar 32 is in engagement with a part of spring contact member 21 before the free end of bar 34 is in engagement therewith. Upon sufficient change of temperature to cause movement of the bar 32, it will move downwardly or toward the base 11, so that the upper portion of the arm 21 will, in effect, be moved toward the left, whereby a scraping action is effected between the cooperating fixed and movable contact members. This, of course, will have the result of cleaning the cooperating contacts without breaking or interrupting the circuit. At a different predetermined temperature, the end 38 of bar 34 will engage the spring contact member 21 and will cause dis-engagement of contact members 23 and 16, then the dis-engagement of 95 contact members 29 and 17 and finally of contact members 31 and 18, it being assumed, of course, that the temperature varies a sufficient amount to cause such action.

Upon the reverse changes of temperature, the reverse sequence of operation will be effected, that is, the cooperating contact members will be moved into engagement and then will be caused to scrape one upon the other to effect a cleaning of the contact members and, therefore, obtain a better engagement therebetween.

The device embodying my invention thus provides a means for effecting a plurality of movements in different directions and in a predetermined sequence in a thermostatic switch embodying a bimetal actuating element. Also the first bimetal bar effects movement of the entire spring contact structure of U-shape and the second bimetal bar effects movement of a portion only of the contact structure of U-shape. I may say that I have found that the disengagement or engagement of the cooperating contact members is effected without vibration or chattering of the contact members, so that any radio devices operated in the neighborhood of a thermostat of this kind are not affected to any appreciable extent.

Various modifications may be made in the device embodying my invention without departing from the spirit and scope thereof, and I desire, therefore, that only such limitations shall be placed thereon as are imposed by the 130

prior art or are set forth in the appended claims.

I claim as my invention:

1. In a thermostatic switch, a base, a fixed contact member on the base, a spring contact bar on said base and a plurality of bimetal members on said base for actuating the spring contact bar in sequence in different directions at right angles to each other relatively to the fixed contact member.

2. In a thermostatic switch, a base, a fixed contact member on the base, a spring contact arm, of substantially U-shape, mounted on the base, and a plurality of bimetal bars located within the spring contact member and supported by the base for actuating the spring contact arm in sequence in different directions at right angles to each other relative to the fixed contact member.

3. In a thermostatic switch, a base, a fixed contact member on the base, a spring contact member, of substantially U-shape, supported by said base, a first bimetal bar mounted on the base and having its free end engaging the spring contact member to effect a scraping movement between the engaged contact members and a second bimetal bar supported by said base and effective to cause a separating movement of the contact members, upon a predetermined change of temperature.

4. In a thermostatic switch, a base, a fixed contact member on the base, a spring contact member operatively supported on the base and spaced therefrom, a bimetal strip having one end mounted on the strip and its other end operatively engaging the spring contact members to effect scraping movement between the contact members, a second bimetal bar having one end resiliently supported on said base and having its other end engaging the spring contact member to cause separation of the contact members upon a predetermined variation of temperature, and means operatively engaging the resiliently-supported end of the second bimetal bar to vary the temperature at which separation of the contact members occurs.

5. A thermostatic switch including a base, a plurality of fixed contact members on the base, a resilient bar providing a plurality of contact arms of different rigidity cooperating with the fixed contact members and a plurality of bimetal bars on the base for actuating the resilient bar in different directions at right angles to each other to effect disengagement between the cooperating contact members in sequence and at different temperatures.

6. A thermostatic switch including a fixed contact, a spring contact arm cooperating with the fixed contact and a pair of bimetal bars engaging the spring contact arm, one of said bimetal bars effecting a scraping movement between the cooperating contact

members and the second bimetal bar effecting separation therebetween.

7. A thermostatic switch including a fixed contact, a spring contact arm cooperating with the fixed contact and a pair of bimetal bars engaging the spring contact arm at different points along its length and effective to actuate it in sequence in different directions at right angles to each other relatively to the fixed contact member.

In testimony whereof, I have hereunto subscribed my name this 13 day of June, 1930.

EARL K. CLARK.
